UNITED STATES PATENT OFFICE.

CHARLES A. STICKNEY, OF ROCKFORD, ILLINOIS, ASSIGNOR TO THE NATIONAL AUTOMATIC TOOL COMPANY, OF RICHMOND, INDIANA, A CORPORATION OF INDIANA.

COMBINED DRILLING AND TAPPING MACHINE.

Application filed June 30, 1924. Serial No. 723,164.

This invention relates to a combined drilling and tapping machine; that is a machine tool provided with a plurality of spindles and adapted simultaneously to perform drilling and tapping operations.

A machine-tool of this nature may be used advantageously for quantity production wherein successive pieces of work require the drilling and tapping of holes in a predetermined arrangement. In the operation of this machine-tool the operator sets up the work on the work-table and performs the drilling operation in the usual way just as though no tapping mechanism was present. While the drilling is being effected a previously drilled piece is being tapped automatically without any attention or effort on the part of the operator. After the tapping operation is completed, the work is again brought to the operator for removal from the work-table. Thus it will be seen that inasmuch as only one set-up is required for the two operations and as no additional time is required for the tapping operation, production is increased substantially 100 per cent, as compared with performing the same operations in separate drilling and tapping machines, without any additional operative cost, or effort on the part of the operator. Furthermore one combined drilling and tapping machine requires substantially less operating floor space than do two separate machines, which likewise effects a substantial saving in factory installation.

An object of this invention is to provide a combined machine having two separate and distinct sets of spindles of which one set is preferably rotated in a single direction and is adapted particularly for drilling and the other set is adapted to be rotated in both forward and reverse directions and may, therefore, perform either drilling or tapping operations, the reverse rotation serving to unscrew the taps from the work after the holes have been tapped.

In some classes of work it is necessary that all of the holes be tapped whereas in other work only certain ones must be tapped. It is therefore an object of this invention to provide a combined drilling and tapping machine in which a plurality of holes may be drilled simultaneously and in which any or all of such holes may be tapped in a

subsequent operation and simultaneously with a similar drilling operation in the next 55 succeeding piece of work.

A further object is to provide automatically acting means for transferring the work from a position in which it is acted on by one series of tools to a position in which it 60 will be acted on by the other series of tools in the next succeeding operation of the machine. This object may be attained by providing a rotary work-supporting table together with power actuated means for rotating the table between successive operations.

A still further object of the invention is to provide, in a combined drilling and tapping machine, a single source of power and improved means operated thereby for rotating 70 all of the tools and for feeding them into and out of the work.

Another object of the invention is so to co-ordinate the tool rotating and feeding mechanisms that the latter will always be 75 maintained proportionate to the former, whereby the taps and drills will always be fed into the work at a speed commensurate with the most efficient speed of rotation of the taps for any desired operation.

A further object is to provide an improved form of rapid feed to bring the tools into contact with the work and to remove them therefrom after a drilling or tapping operation.

Another object of this invention is to provide, in a machine of the character described, automatically acting means for reversing the direction of rotation of the taps at an increased speed after they entered the work 90 a predetermined distance and simultaneously therewith changing the direction of feed of the drill-head.

A further object of the invention is to provide an intermediate speed up-feed for 95 the head, and to render said feed effective during the reverse rotation of the taps to elevate the head at the same speed that the taps are withdrawn from the work.

Still another object is to provide automatically acting means for controlling all of the various trains of mechanism of a combined drilling and tapping machine viz., a rapid power-feed, a slow power-feed, an intermediate speed-feed, drill and tap rotating mechanisms and a tap reversing mecha- 100 105 110 115

nism and so to co-ordinate and synchronize the operation of these mechanisms that the machine, when once set in motion, will automatically perform a complete cycle of operations without manual aid.

To the attainment of this object each of the various mechanisms is preferably actuated by a friction-clutch and in turn these clutches are controlled by cams fixed upon a shaft adapted to be rotated intermittently by means of a suitable cycle control mechanism later to be described.

Another object of the invention is to provide a machine-tool capable of attaining all of the objects hereinbefore enumerated and so to construct the frame work therefor that the machine will be capable of withstanding extremely heavy loads without material deflection, and upon which the tool-head may be more rigidly supported than has heretofore been possible.

This object is attained by providing a heavy base upon which are rigidly supported two ponderous columns upon which the tool-head is slidably mounted. The tops of the columns are preferably tied together by means of a heavy bridge which also serves to support the weight of the tool-head and to house substantially all of the mechanism for elevating and depressing the tool-head and for rotating the spindle drive-shafts.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

45 Fig. 1 is a side-elevation of the combined drilling and tapping machine embodying the present invention. Fig. 2 is a plan of the bridge of the machine showing the drive and feed mechanisms, the cap and cover-plate being omitted. Fig. 3 is a longitudinal vertical section substantially along the line 3-3 of Fig. 2. Fig. 4 is an enlarged vertical section of the left end of Fig. 2. Fig. 5 is a plan of Fig. 4, certain of the mechanism being omitted for the sake of clearness. Fig. 6 is an enlarged vertical section of the opposite ends of the bridge showing, at the right, the rapid drive from the power shaft to the feed-shaft, and at the left the drive from the power shaft, through the cycle-clutch to the cam-shaft. Fig. 7 is an enlarged transverse section through the bridge on the line 7-7 of Fig. 2. Fig. 8 is a gear lay-out showing the means for transmitting power from the main

power-shaft to a cam-shaft, from the power-shaft to a slow spindle drive-shaft and from the slow spindle drive-shaft to a feed-shaft, all later to be described. Fig. 9 is an enlarged section of one of the friction clutches together with its actuating mechanism. Figs. 10, 11 and 12 are front, end, and plan views, respectively, of a cycle-controlling mechanism later to be referred to. Fig. 13 is a horizontal section on the line 13-13 of Fig. 10. Fig. 14 is a vertical section on the line 14-14 of Fig. 13. Fig. 15 is an enlarged front view, partly in section, of the actuating means for the cycle-control mechanism. Fig. 16 is a side view, partly in section of the parts shown in Fig. 15. Fig. 17 is a horizontal section on the line 17-17 of Fig. 15. Fig. 18 is a sectional view of an epicyclic gearing, forming a part of a feeding mechanism later to be described. Fig. 19 is a section on the line 19-19 of Fig. 18. Fig. 20 is a central vertical section of the work-supporting table. Fig. 20^a is a detail section on the line a-a of Fig. 20 showing an intake port for fluid under pressure. Fig. 21 is a section substantially on the line 21-21 of Fig. 20. Fig. 22 is a diagrammatic representation of the mechanism for effecting the rapid up and down feeds of the head. Fig. 23 is a diagrammatic representation of the means for rotating the spindle drive-shafts when both of the sets of spindles are used for drilling. Fig. 24 is a similar view of the tap-spindle rotating mechanism. Fig. 25 is a diagrammatic representation of the tap-spindle rotating mechanism together with the means for effecting slow downward feed of the head when tapping. Fig. 26 is a similar view showing, in full lines, the means for effecting the tap-spindle reverse drive, the intermediate speed up-feed for the head and the means for rotating said spindle and the slow-down feed for the head when the machine is used for drilling only. Figs. 27 and 28 are diagrammatic representations in side and front view, respectively, of a hand-feed for the head. Fig. 29 is a diagrammatic view illustrating the initial flow of fluid under pressure for rotating the bed of the work-table. Fig. 30 is a similar view illustrating the flow of fluid in the second stage in the operation of rotating the bed; and Fig. 31 is a similar view illustrating the flow of fluid when fluid is being exhausted from the various cylinders.

Referring more particularly to the drawings the invention is disclosed, in its preferred form, as embodied in a combined drilling and tapping machine comprising a base A upon which are mounted upright columns C and D. Upon the upper ends of these columns is supported a bridge B which carries substantially all of the actuating mechanism of the machine.

5 A tool-head H, carrying two sets of rotatable spindles s and s', is supported from the bridge and is vertically movable between the columns C and D by means of feed-screws S and S' threaded through nuts N and N' carried at opposite sides of the tool-head and tracking guideways formed in the columns. These screws are rotated by mechanism carried by the bridge as will later be described.

10 Power to operate the various trains of mechanism enters the machine through a power shaft 1 journaled lengthwise of the bridge in bearings 1¹, 2², 3³, 4⁴, 5⁵, and 6⁶ and adapted to be rotated by any suitable 15 means, as for example a pulley P or other prime-mover. From the shaft 1 power is taken, by mechanism later to be described, to rotate the two spindle drive-shafts 2 and 3 which in turn act to rotate the drill-spindles s and tap-spindles s' respectively at 20 variable speeds through the action of suitable change-gears located in a gear-chest 4 carried by the head H. Inasmuch as means for operatively connecting the spindles s and s' with their drive-shafts 2 and 3 and the change-gear mechanisms for varying the speed of rotation of the spindles form no part of the present invention, detailed illustration and description thereof is deemed 25 unnecessary.

30 While this machine will be described as being adapted primarily for the combined operations of drilling and tapping it is to be understood that it may also be used as a straight drilling machine, in which case both sets of spindles will be fitted with drill-points and the reversing mechanism for the one set will be rendered ineffective.

35 Pre-supposing that one piece of work W has been set up on the work-table and drilled, the operation of the machine when used as a combined drilling and tapping machine is as follows:

40 The operator sets up a second piece of work on the table T and, through means later to be described, causes the table to rotate 120 degrees. This rotation places the new piece of work in position to be operated on by the drills driven from the spindle drive-shaft 2 and simultaneously therewith places the previously drilled piece in position to be operated on by the taps driven from the spindle drive-shaft 3. Then, by manipulation of a suitable hand-lever, carried by the head, a cycle-controlling mechanism (later to be described) is tripped into action and causes a partial rotation of a cam-shaft. The cam-shaft carries cams which, in this partial rotation actuate two clutches, one of which disconnects a hand-feed for the head and the other of which puts into action a rapid feed to quickly lower the head to bring the tools into contact with the work. As the tools approach the

work the spindle-rotating mechanism is put 65 into action, the rapid feed is thrown out and a slow power feed is thrown in. This slow feed continues until the drilling and tapping is completed, at which time the slow down-feed is stopped, the direction of rotation of the taps is reversed, an intermediate speed up-feed is put into action to elevate the head at the same speed that the taps are withdrawn. When the taps have cleared the work, the slow up-feed is thrown out, the 75 rotation of the drill-spindle is discontinued, and the rapid up-feed is made effective to rapidly elevate the head and the tools carried thereby. As the head reaches its uppermost position the rapid up-feed and the 80 drill and tap-spindle rotating mechanisms are thrown out and the hand-feed is again connected to permit manual adjustment of the head.

85 The mechanism for producing these various movements and operations is preferably carried by the hollow bridge B and located partially within a cap E closed at its upper side by a cover-plate F. The various trains of mechanism will now be described in detail 90 in their order of operation.

Rapid up and rapid down feeds for the head.

95 Within the cap E and parallel with the power shaft 1, there is journaled, in bearings a¹, a², a³, and a⁴, a reversely rotatable feed-shaft a⁵ to which are secured bevel-pinnions a⁶ and a⁷. These pinions mesh respectively with bevel-gears a⁸ and a⁹ fixed to the feed-screws S' and S. The shaft a⁵ carries, intermediate its ends, two normally ineffective friction-clutches, viz. a rapid down-feed clutch a¹⁰ and a rapid up-feed clutch a¹¹ either of which may be rendered effective to rotate the shaft a⁵. These 100 clutches are, in the normal operation of the machine, operated alternately by means of a fork a¹² secured upon a rod a¹³ journaled at its opposite ends, in the bridge B. The rod a¹³ also carries an arm a¹⁴ supporting a stud or roller a¹⁵ which tracks a cam-groove a¹⁶ formed in a cam-cylinder a¹⁷ fixed to an intermittently rotated cam-shaft X, journaled in bearings x carried by the bridge. 110

115 Power, to rotate the feed-shaft a⁵ counter-clockwise, as viewed from the right end of the machine to elevate the head H, may conveniently be taken from the power shaft 1 by means of a gear a¹⁸ thereon which drives a gear a¹⁹ journaled in a bracket a²⁰ secured to the bridge. (See Figs. 6 and 22.) The gear a¹⁹ in turn drives a gear a²¹ which meshes with and drives a gear a²² carried by one portion of the rapid up-feed clutch a¹¹. Thus when the clutch a¹¹ is made effective by the action of the cam-groove a¹⁶ the feed-shaft a⁵ will be rotated in a direction opposite to that of the power shaft 120 125

and at approximately three-fourths its speed, thereby causing the screws S and S' to elevate the head.

The rapid down-feed is effected by the 5 cam-groove a^{16} shifting the fork a^{12} in the opposite direction thereby actuating the friction-clutch a^{19} . Rigidly connected with the gear a^{21} is a gear a^{23} which meshes with a gear a^{24} secured upon one end of a reversely 10 rotatable shaft a^{25} journaled in the bridge. Upon the opposite end of the shaft a^{25} there is secured a gear a^{26} in mesh with a gear a^{27} carried by a portion of the clutch a^{19} . Thus when the clutch a^{19} is made effective 15 the shaft a^{25} will be rotated in the same direction as the power shaft and the screws S and S' will feed the head H downwardly. In the latter drive the gear a^{22} will also rotate but inasmuch as the clutch a^{11} is then 20 disconnected, this will be merely idle rotation.

Drill-spindle rotating mechanism.

Journalized co-axially with the power shaft 25 1 and adapted, at certain times, to be rotated therewith by means of a friction-clutch b^1 is a bevel-gear b^2 permanently in mesh with a like gear b^3 secured upon the lower end of a stub shaft b^4 . (See Figs. 2, 3, and 30 23.) The clutch b^1 is actuated by a lever b^5 pivoted at b^6 and having one end in engagement with the clutch and carrying at its opposite end a pin or roller b^7 which tracks a cam-groove b^8 formed in a cam-cylinder b^9 secured upon the shaft X. The shaft b^4 is journaled in a standard b^{10} fixed 35 within the bridge and carries at its upper end a pinion b^{11} which drives a gear b^{12} secured upon the upper end of the drill-spindle drive-shaft 2. Thus when the friction-clutch b^1 is rendered effective by its 40 controlling cam b^8 the shaft 2, and thereby the drill-spindles, will be rotated.

As hereinbefore stated this machine may 45 be used solely for drilling, that is drill points may also be fastened in the spindles s' rotated from the drive-shaft 3. When the machine is used in this manner the spindle drive-shaft 3 is driven from the power shaft 50 by means of a bevel-gear b^{13} carried by a friction-clutch b^{14} similar in construction to the clutch b^1 . This clutch is controlled and actuated by a cam b^{15} formed in a cam-cylinder b^{16} secured upon the shaft X, 55 through the medium of a clutch-shifter b^{17} . The bevel-gear b^{13} meshes with and drives a similar gear b^{18} fixed upon the lower end of a stub-shaft b^{19} journaled in a standard 20. The upper end of the shaft b^{19} carries 60 a pinion b^{21} which drives a gear 22 fixed upon the upper end of the drive-shaft 3.

It is to be understood that when the machine is used for both drilling and tapping the clutch b^{14} is maintained ineffective and 65 therefore the drive-shaft is not operated as

described in the preceding paragraph but by means later to be described.

Tap-spindle forward drive.

When the spindles s' are used for tapping 70 the clutch b^{14} is maintained ineffective and the spindle drive-shaft 3 is rotated at a reduced rate as follows. (See Figs. 2, 3, 5 and 24.)

Secured to the power-shaft 1 and adjacent one end thereof is a small gear c' which constantly drives a large gear c^2 fixed to a shaft c^3 journaled in bearings c^4 and c^5 carried by the bridge. Also secured to the shaft c^3 is a small gear c^6 permanently meshing with a large gear c^7 carried by one portion of a normally ineffective friction-clutch c^8 . At a predetermined time in the cycle of operation this clutch is rendered effective to drive a shaft c^9 , by a clutch-shifter c^{10} through the action of a cam-groove c^{11} formed in a cam-cylinder c^{12} , also carried by the shaft X. Secured to the shaft c^9 is a gear c^{13} in mesh with a larger gear c^{14} fixed upon a shaft c^{15} journaled in bearings c^{16} , c^{17} and c^{18} . The shaft c^{15} which forms a part of the tap forward-drive mechanism also forms a part of a slow power-feed for the head H, as will later be described. By utilizing this shaft as a feed-drive shaft, 95 the slow power-feed is always maintained proportionate to the speed of rotation of the taps.

The shaft c^{15} carries at its forward end a bevel-gear c^{16} which drives a like gear c^{17} secured upon a stub-shaft c^{18} journaled in the standard 20. The shaft c^{18} also carries a pinion c^{19} which drives the gear 22 fixed upon the upper end of the spindle drive-shaft 3 to rotate the taps in a forward 105 direction.

Drill and tap power in-feed.

A slow power-feed is provided to move the head H downwardly to feed the drills and 110 taps into the work. As hereinbefore stated power to operate this feed is taken from the shaft c^{15} which, when the machine is used simultaneously for drilling and tapping, is rotated from the main power shaft 1 115 through gears c^1 , c^2 , shaft c^3 , gears c^6 , c^7 , clutch c^8 and gears c^{13} and c^{14} . (See Figs. 2, 4, 8 and 25.) The shaft c^{15} carries, at its extreme rearward end, a gear d^1 which drives a gear d^2 secured upon one end of a 120 short shaft d^3 journaled in a bearing d^4 provided by the bridge. The opposite end of the shaft d^3 carries a gear d^5 which meshes with and drives a larger gear d^6 on a suitable shaft d^7 . Fixed to the gear d^6 is a 125 smaller gear d^8 permanently in mesh with a larger gear d^9 carried by one portion of a normally ineffective friction-clutch d^{10} . This clutch, at certain times is rendered effective by means of a clutch-shifter d^{11} 130

- having a portion provided with a pin or roller which tracks a cam-groove d^{12} formed in a cam-cylinder d^{13} secured upon the cam-shaft X. When the clutch is thrown into action by the cam d^{12} the gear d^9 is caused to rotate the feed-shaft a^5 carrying the bevel-pinions a^6 and a^7 which mesh with like gears a^8 and a^9 fixed to the upper ends of the feed-screws S' and S, respectively. From the foregoing, it will be observed that power is taken from the tap-rotating shaft c^{15} at whatever speed that shaft is rotated and, through suitable reduction-gears, this speed is gradually reduced to drive the feed-screws at a relatively low speed but always proportionate to the speed of the tap-rotating shaft.

When the machine is used solely for drilling, power to rotate the feed-shaft a^5 flows from the power shaft 1 through a partially different train. (See Figs. 2 and 26.) In this instance the spindle drive-shaft 3 is driven from the power shaft 1 through gears b^{13} , b^{18} , shaft b^{19} and gears b^{21} and 22, and power is transmitted from the gear 22 through gears c^{19} , c^{117} , and c^{116} to the shaft c^{15} which it will be perceived, will be rotated in the same direction as when tapping but at a very much higher speed, to wit, the speed of rotation of the drive shaft 1. With the shaft c^{15} driven in this manner the gear d^2 is shifted inward on its shaft to disconnect it from the gear d^1 and to connect it with a gear d^{18} forming a part of an epicyclic reduction gearing (later to be described) which effects a speed reduction equal to the reduction effected by the gears c^1 , c^2 , c^6 , c^7 , c^{13} , c^{14} , etc., when the power is being transmitted therethrough. From the gear d^2 the power to rotate the feed-screws is transmitted thereto as previously described.

The epicyclic gearing may be of conventional form and may comprise an eccentric d^{20} , fixed to the shaft c^{15} as by means of a key d^{21} . (See Figs. 18 and 19.) Loosely journaled upon a bushing d^{22} surrounding the eccentric d^{20} are gears d^{23} and d^{24} of which the former meshes with an internal gear d^{25} formed in a frame d^{26} fixed to the bridge B. The gear d^{24} likewise meshes with an internal gear d^{27} loosely journaled on the shaft c^{15} and upon which is keyed the gear d^{18} . Thus rotation of the shaft c^{15} will, due to the difference in ratio between the gears d^{22} and d^{23} and their respective mates rotate the gear d^{18} at a materially reduced rate in a well-known manner.

Tap-spindle reverse drive.

When the taps have entered the work a predetermined distance the cam c^{11} actuates the clutch-shifter c^{10} which then permits the clutch c^8 to release the shaft c^9 and thus forward rotation of the taps is discon-

tinued. At that instant the downward feed of the head is also discontinued and an upward feed is begun, to raise the head H and the tools carried thereby.

To permit withdrawal of the taps from the work it is necessary that they be rotated in a reverse direction to unscrew them from the holes that they have just previously tapped. This reverse rotation may be at a substantially greater rate than the forward rotation of the taps and may conveniently be effected by mechanism now to be described. (See Figs. 2, 3 and 26.)

Co-axial with the power shaft 1 is a normally ineffective friction clutch e^1 to which is secured a bevel-gear e^2 permanently in mesh with the bevel-gear b^{18} diametrically opposite the gear b^{13} . When the forward rotation of the tap has been stopped the clutch e^1 is caused to lock the gear e^2 to the power shaft 1 which, through gear b^{18} , shaft b^{19} , pinion b^{21} and gear 22 cause reverse rotation in the drive-shaft 3 and thereby in the tap-spindles S'.

It is to be noted that if the drive-shaft 1 is rotated at say 500 R. P. M. in the forward rotation of the taps the shaft c^{15} will be rotated at approximately 40 R. P. M., whereas when the taps are reversed as just previously described the shaft c^{15} will be rotated at substantially the same speed as the drive-shaft. Then, as the connections from the shaft c^{15} to the feed-screws S, S', are the same in both instances it follows that the slow up-feed of the head will be substantially faster than its slow-down feed. This increase in feed is proportionate to the increase in the speed of rotation of the taps when being reversed and withdrawn from the work.

The friction-clutch e^1 is preferably actuated by means of a clutch-shifter e^3 connected at one end to the clutch and carrying, at its other end, a roller e^4 tracking a cam-groove e^5 formed in a cam-cylinder e^6 secured upon the shaft X.

Intermediate-speed up-feed for the head.

Simultaneously with the throwing in of the tap-reverse-drive an intermediate speed up-feed for the head is put into action to elevate the head at the same rate that the taps are withdrawn from the work due to their reverse rotation. This is accomplished by disconnecting the forward-feed clutch c^8 and reversely rotating the feed-drive shaft c^{15} from the spindle drive-shaft 3 through gears 22, c^{19} , shaft c^{118} and gears c^{117} and c^{116} (see Fig. 26). This reverse rotation of the shaft c^{15} is transmitted to the feed-shaft a^5 and then to the feed-screws S and S' as previously described for the slow-down feed except that direction of rotation in all of the parts is reversed and the rate is faster due to the difference in ratio of the

gears between the shaft 1 and the shaft c^{15} . When the taps have cleared the work the clutch e^1 is released and the rapid up-feed clutch a^{11} is actuated to cause rapid elevation of the head.

Hand-feed for the head.

For certain purposes and at certain times, such as when initially setting up a particular class of work, it is desirable to have the head H under manual control. To this end there is provided a hand-feed by means of which the head may be raised or lowered at the will of the operator whenever the power feeds are ineffective. (See Figs. 1, 5, 27 and 28.)

Journaled in the column C is a short shaft f^1 which carries at one end a hand-wheel f^2 and at the other end a bevel-gear f^3 . This gear drives a similar gear f^4 secured upon the lower end of an upright shaft f^5 which carries at its upper end a bevel-gear f^6 permanently in mesh with a gear f^7 fixed to one end of a horizontal shaft f^8 journaled 25 in the bridge. The opposite end of the shaft f^8 carries a worm f^9 which drives a worm wheel f^{10} forming one element of a gear-unit f^{11} loosely journaled on the shaft d^7 . The gear-unit f^{11} also provides a gear 30 f^{12} which drives a gear f^{13} carried by one element of a friction-clutch f^{14} carried by the feed-shaft a^5 . This clutch f^{14} is actuated at certain times, to lock the gear f^{12} to the feed-shaft, by the clutch-shifter d^{11} which 35 also actuates the slow power-feed clutch d^{10} as previously described. Thus when the cam d^{12} causes the clutch-shifter d^{11} to be moved toward the right as viewed in Fig. 2, the hand-feed is made effective.

40 Friction-clutches.

All of the friction-clutches viz a^{10} , a^{11} , b^1 , b^{14} , c^8 , d^{10} , e^1 and f^{14} are substantially the same in construction and it is therefore 45 deemed sufficient to illustrate and describe only one in detail. Fig. 9 shows in longitudinal section the tap-reversing clutch e^1 which may be used as representative of all of the clutches, certain of them being different only in the type of gear supported thereby.

These clutches preferably comprise an internal driving element 50 secured to its driving shaft as by means of a key 51, and 55 an external driven-element 52 loosely journaled on a bushing 53 co-axial with the shaft. The element 52 is formed with a hub 54 upon which is secured, as by key 55, a gear as e^2 . In certain of the clutches the hub 54 carries a spur-gear instead of the bevel-gear e^2 .

The driver 50 is formed with a plurality of external ribs or splines 55 which interfit with similar splines formed within circular friction-plates 56 whereby the plates are caused

to rotate with the driver 50. A similar series of plates 57 are driven by internal ribs 58 formed in the part 52. Intermediate the overlapping portion of the plates 56 and 57 are friction-washers 59 one of which bears 70 against an annular flange 60, secured at one end of the driver 50. Slidably secured to the opposite end of the driver 50 is a clutch-ring 61, adapted to be shifted axially of the shaft by a clutch-shifter as e^3 , having one 75 arm engaging a shiftable spool 62 slidably mounted co-axially with the shaft. The opposite arm of the clutch-shifter carries a roller as e^4 which tracks a cam-groove as e^5 formed in the cam-cylinder as e^6 slidably 80 secured to the shaft X as by a spline 63. Intermediate the spool 62 and the clutch-ring 61 is an anti-friction thrust bearing 64 which, when the arm e^3 is shifted toward the clutch, forces the clutch-ring toward the 85 fixed flange 60 thereby causing the washers 59 to lock together the plates 56 and 57 and thereby the driving-element 50 and the driven-element 52.

The cam-cylinder e^6 is splined to the shaft 90 X and is normally maintained in contact with a fixed collar 65 by a heavy coil-spring 66 surrounding the shaft X and located intermediate the cam-cylinder and a fixed collar 67.

The operation of the clutch is as follows: Revolution of the cam-cylinder e^6 , in the direction of the arrow, will first move the roller e^4 to the left and therefore the spool 62 will be moved to the right until the washers 59 are fully compressed and the parts 50 and 52 are securely locked together. Inasmuch as the lower arm of the clutch-shifter is held against further movement toward the clutch a further rotation of the 105 cam-cylinder will cause said cylinder to be moved to the right on the shaft X against the pressure of the spring 66 until the full throw of the cam-groove e^5 has been utilized. This maintains the friction-clutch under 110 heavy spring-pressure until a further rotation of the cam-cylinder e^6 causes the roller to ride down the cam-groove e^5 , which first permits the cylinder e^6 to be moved lengthwise of the shaft by the spring 66 until it 115 contacts with the fixed collar 65 and then to release the pressure on the friction-clutch.

It is to be noted that the cams formed in the cam-cylinders a^{17} and d^{13} are each adapted to operate two friction-clutches and therefore the cam-cylinders are maintained between opposed springs 66 and 66' which permit the cam-cylinders to yield in either direction dependent upon which clutch is 120 actuated.

Clutch throw-out.

As previously stated this machine may be used for the combined operations of drilling and tapping or it may be used for drilling 120

only. In the former case the clutch b^{14} is maintained ineffective and in the latter case the tap forward-drive clutch c^8 and the tap-reverse clutch e^1 are maintained ineffective.

5 This throwing out of action of the various clutches may be effected by disconnecting their shifters from their respective actuating cams on the shaft X. Disconnection of the clutch-shifters from the cams may be effected 10 in any suitable way such as for example, as by shifting the upper arms of the clutch-shifters b^{17} , e^8 , and e^{10} lengthwise of their supporting shafts to withdraw their rollers from the cam-grooves and then holding them 15 in their adjusted positions by means of suitable set-screws 100 threaded through the hubs of the clutch-shifters and adapted to bear against said shafts.

20 *Cycle-controlling mechanism.*

As hereinbefore stated the cam-shaft X is rotated intermittently and the cams carried thereby are so arranged that the various clutches are actuated in a predetermined 25 sequence to perform a complete drilling and tapping operation. This intermittent rotation of the cam-shaft is effected by means of a cycle-control mechanism now to be described. (See Figs. 1, 2, 6 and 10 to 14.)

30 The gear c^1 on the drive-shaft 1 constantly drives a gear g^1 loosely journaled on a short shaft g^2 secured within the bridge. Fixed to the gear g^1 is a smaller gear g^3 in mesh with a larger gear g^4 . The latter gear drives 35 a gear g^5 loosely journaled coaxial with a shaft g^6 , rotatably journaled in a cycle-clutch casing g^7 secured within the bridge cap E. The gear g^5 is thus kept in constant rotation and at certain times, through the medium of 40 a cycle-clutch indicated generally as G, partially rotates the shaft g^6 as will later be described. Fixed to the shaft g^6 , as by means of a key g^8 , is a gear g^9 which meshes with and drives a gear g^{10} fixed to the cam-shaft 45 X whenever the shaft g^6 is turned. The ratio between the gears g^9 and g^{10} is as 1 to 2 and therefore as a completed rotation of the cam-shaft is required to perform a single drilling and tapping operation it is evident 50 that shaft g^6 and the parts carried thereby must be given two complete rotations to effect a single operation of the machine.

Fixed to the head H in any suitable place, such as for example as to the nut N, is a plate g^{11} provided with a T-slot g^{12} within 55 which is slidably mounted a bearing-casting g^{13} adapted to receive the lower ends of two shafts g^{14} and g^{15} supported at their upper ends in bearings provided by a casing g^{16} carried by the cap E.

The shaft g^{14} has secured to it at its lower end a lever g^{17} provided at opposite sides of the shaft with spring-plungers g^{18} and g^{19} adapted, in the vertical movements of the 60 head H, to contact with suitable dogs g^{20} ,

g^{21} , g^{22} , and g^{23} adjustably secured in T-slots g^{24} and g^{25} also formed in the plate g^{11} , for a purpose later to be explained.

The shaft g^{15} likewise carries at its lower end a lever g^{26} and to its upper end is secured, within the casing g^{16} , an arm g^{29} , connected by a link g^{30} to bell-crank lever g^{31} pivoted at g^{32} within the cap E. A second link g^{33} connects the bell-crank lever with an arm g^{34} fixed to a shaft g^{35} journaled in the casing g^7 . The shaft g^{35} also has secured to it a dog g^{36} later to be referred to.

Upon the upper end of the shaft g^{14} there is secured an arm g^{37} also connected by a link g^{38} to a bell-crank lever g^{39} pivoted at g^{32} . The bell-crank g^{39} has pivoted to it one end of a link g^{40} of which the other end is pivoted to an arm g^{41} secured to a rock-shaft g^{42} carrying at one end a dog g^{43} similar to the dog g^{36} .

Within the cycle-clutch casing g^7 , and diametrically opposite the rock-shaft g^{42} , there is journaled a rock-shaft g^{44} to one end of which is secured a dog g^{45} similar to the dogs g^{36} and g^{43} . The opposite end of the shaft g^{44} carries a horizontally projecting arm g^{46} connected by a link g^{47} to an arm g^{48} connected with the arm g^{41} and projecting in the opposite direction to the arm g^{46} . Thus, oscillations of the arm g^{41} , shaft g^{42} and dog g^{43} will be transmitted in the opposite direction to the arm g^{46} , shaft g^{44} and dog g^{45} for a purpose later to be explained.

The construction of the cycle-clutch G is as follows: Fixed to the shaft g^6 as by means of a key g^{50} and pin g^{51} is a drum g^{52} provided with three equally spaced apertures g^{53} within each of which are located balls g^{54} and g^{55} the combined diameters of which is slightly greater than the width of the drum. Secured to the periphery of the drum are two 100 arcuate plates g^{56} and g^{57} carrying respectively clutch-elements g^{58} and g^{59} adapted at certain times to engage clutch-teeth g^{60} on the side of gear g^5 to rotate the drum g^{52} .

Loosely journaled on the shaft g^6 , adjacent the drum g^{52} is a circular plate or disk g^{61} provided with recesses g^{62} adapted to receive the balls g^{55} . The disk g^{61} is also formed with a lug g^{63} adapted in its rotary movements to contact alternately with the ends of the dogs g^{36} , g^{43} and g^{45} .

Referring particularly to Figs. 13 and 14 it will be seen that rotation of the gear g^5 will, through the clutch-members g^{58} and g^{59} and clutch-teeth g^{60} , rotate the drum g^{52} . Also that rotation of the drum will, through the balls g^{54} and g^{55} and the walls of the recesses g^{62} , rotate the disk g^{61} , and through the key g^{50} and pin g^{51} rotate the shaft g^6 . The shaft g^6 carries the gear g^9 which being in mesh with gear g^{10} will rotate the cam-shaft X.

When the lug g^{63} engages the end of any one of the dogs g^{36} , g^{43} , or g^{45} the rotation

of the disk g^{61} will be arrested. However a continued rotation of the gear g^5 and drum g^{52} will cause the balls g^{55} to ride up the inclined wall of the recesses g^{62} forcing the balls g^{54} and thereby the gear g^5 away from the drum against the action of a spring-pressed plunger g^{64} . This lateral movement of the gear will disengage the clutch-teeth g^{60} from the clutch-elements g^{63} thereby stopping the rotation of the drum, shaft g^6 and finally the cam-shaft X.

Projecting laterally from the disk g^{61} are three pins g^{65} which extend into arcuate pockets g^{66} formed in a side of the drum. 15 These pins bear against one end of coil-springs g^{67} located in the pockets and which have their opposite ends in engagement with walls g^{68} . Thus when rotation of the disk is stopped by one of the dogs further rotation of the drum by the gear g^5 compresses the springs g^{67} and maintains them under tension as long as the lug is held by the dog. When the dog is removed from the lug the power stored in the spring causes 20 the disk g^{61} to be snapped ahead to again align the recesses g^{62} with the balls g^{55} . At this time the spring-pressed plunger g^{61} shifts the gear laterally and again engages the clutch-teeth g^{60} with the clutch-members g^{63} , thus permitting another partial rotation 25 of the drum, disk, cam-shaft, etc., until the lug g^{63} again engages one of the dogs which disconnects the clutch and stops rotation of the parts as previously described.

30 The operation of the cycle-control mechanism is as follows: Considering the parts to be in their stopped position at the end of a drilling and tapping operation, that is with the head H in its uppermost position and with the hand-feed therefor connected and the lug g^{63} against the end of the dog g^{26} . (See dotted line position Fig. 14.) The operator, by manipulation of the hand-lever g^{26} , carried by the head, turns the shaft g^{15} , which 35 through the mechanism described rocks the shafts g^{55} and lifts the dog g^{26} out of the path of the lug g^{63} . This immediately causes engagement of the cycle-clutch G and consequently the parts are rotated until the lug g^{63} engages the dog g^{43} . This partial rotation also causes a partial rotation of the cam-shaft X and the cams carried thereby which are so arranged that the hand-feed 50 will be thrown out and the rapid down-feed will be thrown in.

When the rapid down-feed has lowered the head H until the drills and taps have nearly reached the work, the dog g^{26} will engage the plunger g^{19} which will rock the lever g^{17} and thereby the shaft g^{14} . This causes the shaft g^{12} to be rocked and the dog g^{43} to be withdrawn from the lug g^{63} . The parts controlled by the cycle-clutch are again given a partial rotation until the lug g^{63} engages the dog g^{45} . This last partial rota-

tion of the cam-shaft disconnects the rapid down-feed, connects the slow power down-feed and starts rotation of the drill and tap-spindles.

When the drills and taps have entered the work a predetermined distance the dog g^{21} engages the plunger g^{18} which rocks the lever g^{17} , and thereby the shaft g^{14} , in the opposite direction. This rotation of the shaft g^{14} rocks the shaft g^{12} which lifts the dog g^{45} out of the path of the lug g^{63} . The cycle-clutch then again operates and the parts are rotated until the lug engages the dog g^{43} , the manually controlled dog g^{26} being at this time, swung out of the path of the lug by means of a dog g^{27} engaging a plunger g^{28} carried by the lever g^{26} . This partial rotation of the cam-shaft stops the forward rotation of the tap-spindles, stops the slow down-feed of the head, and starts a reverse-drive for the tap-spindles and an intermediate speed up-feed for the head.

As the taps leave the work the plunger g^{19} engages the dog g^{22} which rocks the lever g^{17} and again lifts the dog g^{43} from the lug g^{63} which then moves into contact with the dog g^{45} . During this last movement the cams on the cam-shaft throw out the forward drive for the drill-spindles, disconnect the intermediate speed up-feed, stop the reverse drive for the tap-spindles and throw in the rapid up-feed.

When the head reaches its uppermost position the lever g^{17} is rocked by the dog g^{23} coming into contact with the plunger g^{18} . 100 This lifts the dog g^{45} which permits the lug to move into contact with the dog g^{26} which has then been returned to its effective position in the path of the lug. This final movement of the cam-shaft causes the rapid up-feed to be disconnected and the hand-feed to be thrown in, thus bringing the machine to rest with the manual feed effective.

While the plungers g^{18} and g^{19} are shown and described as being spring-pressed it is to 110 be understood that the springs are of a strength sufficient to insure swinging of the lever g^{17} whenever the plungers are engaged by the dogs. This construction is provided merely to cushion the contact between the dog and the plunger.

An equalizing spring g^{70} connected to arms g^{71} and g^{72} projecting from the arms g^{41} and g^{46} respectively, acts to return the dogs g^{43} and g^{45} and the lever g^{17} to their 120 normal effective positions after the lever g^{17} has been shifted.

Work-supporting table.

Secured to the base of the machine, beneath the head H and between the columns C and D is the work-supporting table T. This table preferably comprises a fixed standard or base 31 upon which is rotatably mounted the work-bed 32. The bed 32 is 125 130

adapted to support the work and to be rotated 120 degrees between successive drilling and tapping operations.

In the operation of the machine the operator is stationed before the table at a convenient place for securing the work to the table and later removing it therefrom. After the work has been properly located on the table, as by means of suitable jigs or fixtures and after the head H has been elevated, the operator, by manipulation of a suitable control-lever, causes a partial rotation of the bed to position the work, just secured thereto, beneath the drill-spindles. Power to rotate the bed may be supplied by fluid under pressure and may be controlled as will later be described.

During the drilling of the work just presented to the drills the operator attaches a second piece of work to the bed and after the drilling is completed again causes the table to rotate 120 degrees as before described. The operation is repeated and the work which has been drilled is placed beneath the tap-spindles where any, or all, of the holes may be tapped. The next movement of the bed returns the first piece of work (which has then been drilled and tapped) to the operator who removes it from the bed and replaces it with a new piece.

It is highly desirable that the bed be locked against movement during the time that the drilling and tapping is being effected. To this end a shot-bolt 33 is slidably mounted in the standard 31 and when the bed has been rotated sufficiently to bring the work to the proper position this bolt is forced upwardly to cause its end 34 to enter a socket 35 formed in a hardened bushing 36 carried by the bed 32; one of these bushings being provided for each operative position of the table.

As shown in Fig. 20 the standard 31 is formed with an annular flange 37 which supports an annular bearing ring 38 upon which the bed 32 is supported. The standard is also provided with an internal annular flange 39 which supports, coaxial with the bed, as by means of a flange 40, a cylinder 41. Slidably mounted within the cylinder is a piston 42, carrying at its lower end the usual cupped leather 43, and having its upper end reduced and provided with a plurality of vertical ribs or splines 44 adapted to slide between ribs 45 formed in the inner surface of cylinder 46 fixed to and depending from the upper end of the cylinder 41.

Means, later to be described, is provided for moving the piston 42 vertically in the cylinder and in such movement relative rotation between the piston and the cylinder is prevented by the intermeshing of the teeth 44 and 45.

Rotatably journaled in the bed 32 and coaxial therewith is a post 47 which extends

downwardly through the cylinder 46 and is formed with a plurality of helical grooves 48. These grooves interfit with teeth 49 formed interiorly of the upper portion of the piston 42. Thus it will be perceived that upward movement of the piston 42 will, through the action of the teeth 49 and grooves 48, cause rotation of the post 47 in one direction and downward movement of the piston will cause rotation of the post in the opposite direction. The post 47 is held against lengthwise movement in the bed in one direction by means of a plate 150 secured to the upper end of the post as by screws 151, which plate rests upon the upper surface of a portion 152 of the bed. Movement of the post in the opposite direction is prevented by an integral flange 153, which abuts the underside of the portion 152. The flange 153 is preferably formed at its periphery with a series of ratchet-teeth 153^t which are engaged by a pawl 154 secured upon a pin 155 journaled at 156 in the bed. A spring 157 connected at one end to a pin 158 carried by the pin 155 and at its other end to a pin 159 fixed in the bed normally acts to hold the pawl 154 in engagement with the ratchet-teeth 153^t.

From the foregoing it will be seen that when the post is rotated anti-clockwise as viewed in Fig. 21 the bed 32, through the ratchet 153^t and pawl 154, also will be rotated, whereas during clockwise rotation of the post the pawl will slip around the ratchet and no motion will be transmitted to the table.

A coil-spring 160 located within the cylinder 41 intermediate the piston 42 and a flange 46^a of the cylinder 46 acts to force the piston 42 downwardly when the fluid pressure beneath the piston has been relieved.

The shot-bolt 33 for locking the bed in its adjusted positions is slidably mounted in a chamber 161 formed in an extension 162 of the standard 31 and is preferably provided with annular grooves 163 and 164 adapted to receive a spring-pressed detent 165. The groove 163 receives the detent when the bed is unlocked and the groove 164 receives it when the bolt 33 has been projected upwardly to cause the end 34 to enter the socket 35. The bolt 33 is adapted to be moved lengthwise in the chamber 161 by a bell-crank lever 166 pivoted upon a shaft 167, journaled in a bracket 168 carried by the extension 162. One arm of the bell-crank engages an annular groove 169 formed in the lower end of the bolt 33 and the other arm is connected with a fluid-actuated piston 70 later to be referred to.

A hand-lever 71 is secured to the shaft 167 and serves to rock the bell-crank 166 to withdraw the bolt 33 from the bed and simultaneously therewith to move the piston 70 inwardly in its cylinder 72 thereby releas-

ing fluid under pressure to cause elevation of the piston 42 and thereby rotation of the work-supporting bed 32. At a certain point in the upward movement of the piston 42 a suitable port is opened which admits pressure behind the wall 73 of the piston 70 thereby forcing the piston outwardly causing it to rock the bell crank which in turn lifts the bolt 33 to lock the bed as previously described. Outward movement of the piston 70 also shuts off the fluid pressure whereupon the piston 42 is forced downwardly by the spring 160.

Means is provided for preventing manipulation of the hand-lever until the piston has been returned to its lower-most position. This means comprises a rod 75 slidably mounted in a bore 76 formed in the standard 31 and in the flange 40. Operatively connected with the rod 75, at its lower end is a lever 77 pivoted at 78 to a bracket 79 carried by the base 31^a of the standard. The lever 77 is normally forced upwardly by a coil-spring 80 located between the lever and the base 31^a. The cylinder 41 is closed at its lower end by a plate 41^a formed with a bore 41^b within which is slidably fitted a pin 81 having a head 81^a engaging the lever 77. With the piston 42 raised the spring lifts the lever 77 until the upper end 75^a of the pin 75 contacts with the underside of the extension 70^a of the piston 70 and when the piston 70 is forced outwardly to cause the bolt 33 to lock the bed 32 against turning, the pin 75 is moved upwardly thereby intersecting the path of travel of the end 70^a. With the pin 75 in this position it prevents the piston from being forced inwardly by the hand-lever 71 and therefore retraction of the bolt 33 and turning on the fluid pressure is precluded.

Threaded through the piston 42 and maintained in adjusted positions by a lock-nut 82 is a rod 83 adapted, upon lowering of the piston 42 to contact with the pin 81 and thereby retract the pin 75 out of the path of the piston 70. With the pin 75 retracted the bolt 33 is held in its uppermost position by the detent 65 engaging the annular seat 64 until the hand-lever is again depressed.

Fig. 20 shows the position of the parts immediately after actuation of the hand-lever 71 to cause rotation of the bed 32, the dotted lines showing the positions from which the bolt 33, bell-crank lever 166, and piston 70 have just been moved. The bolt 33 having been withdrawn from the socket 35, the bed is then free to be rotated which is effected as follows: Fluid under pressure enters the cylinder 72 through a port 84 (which has now been opened by movement of the portion 70^b of the piston 70) and flows through the passage 85, as shown by the arrows *p*, into a chamber 86, thereby closing the ball check-valve 87. The fluid

then enters and follows a passage 88 (still in the direction of the arrows *p*) into a cylinder 89 between portions 90^a and 90^b of a piston 90 slidably fitted within the cylinder. From the cylinder 89 the fluid passes through a passage 91 and finally enters the cylinder 41 beneath the piston 42, through a port 92. Pressure beneath the piston 42 causes it to be forced upwardly in the cylinder 41, against the action of the spring 160, until the bottom of the piston passes a port 93. This upward movement of the piston on the post 47 causes rotation of the bed 32 and permits the lever 77 and pin 75 to rise under the action of the spring 80 as hereinbefore explained. The fluid under pressure then flows through a passage 94 in the direction of the arrow *p*, entering the cylinder 89 behind the portion 90^b and forcing the piston outwardly against the action of a spring 95. This movement of the piston closes a port 96 in the passage 88 and opens a port 97. Closure of the port 96 stops the flow of fluid through the passage 91 and opening of the port 97 permits the fluid to enter the cylinder 89 therethrough and thence backwardly through the passage 94 in the direction of the arrows *b*, thus fluid is still admitted into the cylinder beneath the piston 42. Fluid also passes from the cylinder 89 through a port 98 into the cylinder 72 behind the wall 73 of the piston 70 thus forcing the piston 70 outwardly to rock the bell-crank and to force the bolt 33 upwardly until its upper end contacts with the under surface 32^a of the bed 32. Inasmuch as the port 84 is still open fluid under pressure continues to flow through passages 85, 88, port 97 and passage 94 into the cylinder 41 and continues to elevate the piston 42 and thereby rotate the bed 32 until one of the sockets 35 is brought into registry with the end 34 of the bolt 33. When the socket 35 and end 34 are brought into registry, pressure on the wall 73 forces the piston outwardly thereby rocking the bell-crank lever which shoots the bolt 33 upwardly and projects the end 34 into the socket 35. The bolt 33 is maintained in this position by the spring-detent until another depression of the hand-lever 71. As the end 70^a of the piston 70 clears the end 75^a of the pin 75 the latter is forced upwardly by the spring and remains in that position until the piston is lowered and again rocks the lever 77. When the piston 70 moves outwardly in the cylinder the portion 70^b closes the intake port 84, thereby cutting off the fluid under pressure and the reduced portion 70^c is aligned with an exhaust-port 70^d. With the fluid pressure discontinued and the exhaust-port 70^d open, the spring 160 forces downwardly on the piston 42 and the spring 95 returns the piston 90 to its original position. As the piston 42 is forced downwardly by the

spring 160 the fluid beneath the piston is exhausted through port 92, passage 91, port 96, passages 88 and 85 and out through port 70^a and passage 100 to the atmosphere, all in the direction of the arrows *e*.

Return of the pistons 70 and 90 exhaust the air from the cylinders 72 and 89 through port 98, passage 94, port 93, which is then above the piston 42, and out through a port 101 to the atmosphere all in the direction of the arrows *y*. Outward movement of the piston 90 exhausts the air in that portion of the cylinder 89 containing the spring 95 through ports 102 and 103 and then through passage 100.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:

Having thus revealed this invention, I claim as new and desire to secure the following combinations and elements, or equivalents thereof, by Letters Patent of the United States:—

1. A machine-tool combining a column; a tool-head adjustably mounted on said column; a power shaft; a plurality of spindle drive-shafts operatively connected with said power shaft and extending into said tool-head; a plurality of sets of spindles rotatably journaled in said tool-head; a uni-directional drive between the spindles of one set and one of the spindle drive-shafts; and multi-directional drive between the spindles of another set and another of said spindle drive-shafts.

2. A machine-tool combining a tool-head; drill and tap spindles rotatably mounted in said tool-head, a power shaft; a plurality of spindle drive-shafts individually connected with said power shaft and extending into said tool-head; and means for rotating said spindle drive-shafts at unequal speeds from a single speed in the power shaft.

3. A machine-tool combining a tool-head; drill and tap spindles rotatably mounted in said tool-head, a power shaft; a plurality of spindle drive-shafts individually connected with said power shaft and extending into said tool-head; and means for simultaneously rotating said spindle drive-shafts at unequal speeds and alternately in like and unlike directions from a single speed in the power shaft.

4. A machine-tool combining a tool-head; individual sets of drill and tap spindles rotatably mounted in said tool-head; a power

shaft; a plurality of spindle drive-shafts individually connected with said power shaft and extending into said tool-head and each adapted to drive the spindles of one of said sets; means for simultaneously rotating said spindle drive-shafts in like directions from said power shaft; and automatic means to reverse the direction of rotation of one of said drive-shafts and the spindles driven thereby.

5. A machine-tool combining a tool-head; spindles rotatably mounted in said tool-head, a power shaft; a plurality of spindle drive-shafts operatively connected with said power shaft and extending into said tool-head; separate trains of mechanism for simultaneously rotating said spindle drive-shafts in like directions and at unequal speeds from a single speed in the power shaft; another train of mechanism for rotating one of said spindle drive shafts in a reverse direction; and an automatically actuated clutch for controlling the action of each train.

6. A machine-tool combining a tool-head; a plurality of sets of spindles rotatably mounted in said tool-head; a power shaft; a single train of mechanism for rotating the spindles of one of said sets from the power shaft; and a plurality of trains of mechanism for rotating in forward and reverse directions the spindles of another set from said power shaft.

7. In a machine-tool, in combination, a tool-head; a set of spindles rotatably mounted in said head; a uni-directionally rotating constant speed power shaft; and means for rotating said spindles from said power shaft at unequal speeds in opposite directions.

8. A machine-tool combining a tool-head; a power shaft; a plurality of sets of spindles rotatably carried by said tool-head; means actuated by said power shaft for raising and lowering said tool-head; and means actuated by said power shaft for rotating the spindles of one set in one direction during one movement of the head and in the opposite direction during another movement of the head.

9. A machine-tool combining a tool-head; a power shaft; a plurality of sets of spindles rotatably carried by said tool-head; means actuated by said power shaft for raising and lowering said tool-head; means actuated by said power shaft for rotating the spindles of one set in one direction during one movement of the head and in the opposite direction during another movement of the head; and means for changing the direction of rotation of the spindles simultaneously with the change in direction of movement of the head.

10. A machine-tool combining a tool-head; a support therefor; a power shaft, independent trains of mechanism actuated by said power shaft for moving said tool-head relatively to its support, first at a relatively

fast rate, second at a relatively slow rate, third at an intermediate rate and fourth at a relatively fast rate; and means for consecutively rendering effective said trains of mechanism.

11. A machine-tool combining a tool-head; a support therefor; a power shaft, independent trains of mechanism actuated by said power shaft for moving said tool-head relatively to its support, first at a relatively fast rate, second at a relatively slow rate, third at an intermediate rate and fourth at a relatively fast rate; and means actuated by the movement of said tool-head for consecutively rendering effective said trains of mechanism.

12. A combined drilling and tapping machine including in combination, a tool-head; a plurality of sets of spindles rotatably carried by said head; drills secured in the spindles of one set; taps secured in the spindles of another set; means for simultaneously rotating in the same direction said drill and tap-spindles; and means for reversing the direction of rotation of said tap-spindles.

13. A combined drilling and tapping machine including in combination, a tool-head; a plurality of sets of spindles rotatably carried by said head; drills secured in the spindles of one set; taps secured in the spindles of another set; a power shaft; independent trains of mechanism for rotating the spindles of each set from said power shaft; and means for changing the direction of rotation of said tap-spindles.

14. A combined drilling and tapping machine including in combination, a tool-head; a plurality of sets of spindles rotatably carried by said head; drills secured in the spindles of one set; taps secured in the spindles of another set; a power shaft; independent trains of mechanism for rotating the spindles of each set from said power shaft; and means for simultaneously changing the speed and direction of rotation of said tap spindles.

15. In a combined drilling and tapping machine, a tool-head; a plurality of drill-spindles rotatably mounted therein; a plurality of tap-spindles rotatably mounted in said head; a work-support; means for moving said head toward and from said work-support; means for rotating said drill and tap spindles in a forward direction when said head is approaching said work-support; and means for reversing the direction of rotation of said tap-spindles as said head recedes from said work-support.

16. In a combined drilling and tapping machine, a tool-head; a plurality of drill-spindles rotatably mounted therein; a plurality of tap-spindles rotatably mounted in said head; a work-support; means for moving said head toward and from said work-support; independent means for rotating said drill and tap-spindles in a forward

direction when said head is approaching said work-support; and means for reversing the direction of rotation of said tap-spindles during a continued forward rotation of said drill-spindles and as said head recedes from said work-support.

17. A machine-tool combining a tool-head; a plurality of sets of spindles rotatably carried by said head; taps carried by one of said sets; means for lowering said tool-head at a predetermined relatively slow rate; means for raising said tool-head at a materially faster rate; and means for rotating said tap spindles in opposite directions at speeds proportionate to the slow and fast translation of said tool-head.

18. A machine-tool combining a tool-head; a plurality of sets of spindles rotatably carried by said tool-head; drills secured in the spindles of one set; taps secured in spindles of another set; a relative fast feed for lowering said tool-head a predetermined distance; a relative slow feed adapted to give said head a further downward feed; means for rotating said drill and tap-spindles at relatively slow rates during the final downward movement of said tool-head; means, independent of the downward feed, for raising said head; means for rotating said tap-spindles in a reverse direction and at an increased speed; and independent means for discontinuing the rotation of the tap-spindles and for rapidly elevating said head when said taps have been withdrawn from the work.

19. A machine-tool combining two columns; a bridge connecting said columns; a tool-head supported by said bridge and slidably mounted between said columns; a plurality of sets of spindles rotatably carried by said tool-head; drills carried by the spindles of one set; taps carried by the spindles of another set; a power shaft; a single train of mechanism for rotating the spindles of one set from said power shaft; a plurality of trains of mechanism for rotating the spindles of another set; a plurality of trains of mechanism actuated by said power shaft for translating said tool-head between said columns; and means for synchronizing the action of said spindle rotating means and said tool-head translating means.

20. A machine-tool combining a frame comprising two upright columns and an overlying bridge element; a translatable tool-head movable on said frame; a plurality of sets of rotatable spindles carried by said tool-head; means for translating said head at relatively rapid and slow rates, said rapid feed comprising a power shaft journaled in said bridge; a feed-screw supported by said bridge and operatively connected with said tool-head; a nut carried by said tool-head and having a threaded connection with said feed-screw; a feed-shaft journaled

- in said bridge; means actuated by said feed-shaft for effecting relative rotation between said nut and said screw; and a gear-train operatively connecting said power and feed shafts.
21. A machine-tool combining a frame comprising two upright columns and an overlying bridge element; a translatable tool-head movable on said frame; a plurality of sets of rotatable spindles carried by said tool-head; means for translating said head at relatively rapid and slow rates, in opposite directions, said rapid feed comprising a power shaft journaled in said bridge; a feed-screw supported by said bridge and operatively connected with tool-head; a nut carried by said tool head and having a threaded connection with said feed-screw; a feed-shaft journaled in said bridge; means actuated by said feed-shaft for effecting relative rotation between said nut and said screw; two normally inoperative gear trains connecting said power and feed-shafts; and means for alternately rendering effective said two gear trains.
22. In a machine-tool, in combination, a translatable tool-head; a feed-screw operatively connected with said head; a feed-shaft; a power shaft; means for rotating said feed-screw from said power shaft at a plurality of rates in both forward and reverse directions; said last-named means including two pairs of normally ineffective clutches loosely journaled on said feed-shaft; means for rotating said clutches at different speeds and in opposite directions from said power shaft; a single clutch-shifter for actuating each of said pairs of clutches; and a rotatable cam actuated intermittently from said power shaft and adapted to move said clutch-shifters to cause them alternately to actuate said clutches to connect one of them to said power shaft.
23. A machine-tool combining a tool-head; two independent sets of spindles carried thereby; a drive-shaft for each of said sets; operative connections between said drive-shafts and said sets of spindles; a power shaft; and duplicate means for synchronously rotating said drive-shafts from said power shaft.
24. A machine-tool combining a tool-head; two independent sets of spindles carried thereby; a drive-shaft for each of said sets; operative connections between said drive-shafts and said sets of spindles; a power shaft; duplicate means for synchronously rotating said drive-shafts forwardly from said power shaft; means independent of said duplicate means for forwardly rotating one of said spindle drive-shafts; and means for rendering effective either of said rotating means for said one of said spindle drive-shafts.
25. A machine-tool combining a tool-head; two independent sets of spindles carried thereby; a drive-shaft for each of said sets, a power shaft; means actuated by said power shaft for rotating both of said spindle drive-shafts in the same direction; and independent means for giving reverse rotations to one of said spindle drive-shafts.
26. A machine-tool combining a tool-head; two independent sets of spindles carried thereby; a drive shaft for each of said sets, a power shaft; means actuated by said power shaft for rotating both of said spindle drive-shafts in the same direction; independent means for giving reverse rotations to one of said spindle drive-shafts; and means for selectively rendering effective either of said rotating means for said one of said spindle drive-shafts.
27. A machine-tool combining a tool-head a plurality of sets of spindles carried thereby; a spindle drive-shaft operatively connected with each of said sets of spindles; taps carried by the spindles of one set; drills carried by the spindles of another set; means actuated by said power shaft for rotating said drill-spindles at a relatively fast rate; and means independent of said drill-spindle rotating means for rotating said tap-spindles at a relatively slow rate.
28. A machine-tool including in combination, a power shaft; a tap-spindle drive-shaft; an operative connection between said power shaft and said drive-shaft for rotating the latter in a forward direction at a predetermined slow speed; said connection including a first train of speed-reduction gearing constantly rotated by said power shaft; a second set of speed-reduction gearing operatively connected with said drive-shaft and normally disconnected from said first set of reduction gearing; a clutch intermediate said sets of gearing and means for actuating said clutch to cause it to establish a driving connection between said sets of gearing.
29. A machine-tool including in combination, a power shaft; a tap-spindle drive-shaft; a first driving connection between said power shaft and said drive shaft for forwardly rotating the latter; a second driving connection between said power shaft and said drive-shaft for reversely rotating the latter; a controlling clutch embodied in each of said driving connections; and automatically actuated means for alternately shifting said clutches to alternately render effective said driving connections.
30. A machine-tool including in combination, a power shaft; a tap-spindle drive-shaft; a first driving connection between said power shaft and said drive-shaft for forwardly rotating the latter; a second driving connection between said power shaft and said drive-shaft for reversely rotating

the latter; a controlling clutch embodied in each of said driving connections; a clutch-shifter for each of said clutches; a rotatable cam operatively connected with each of said clutch-shifters; and automatic means for rotating said cams to effect alternate engagement of said clutches.

31. A machine-tool combining a tool-head; a plurality of spindles rotatably carried by said tool-head; taps secured in said spindles; a spindle drive-shaft; operative connections between said drive-shaft and said spindles; a power shaft; a tap forward-drive between said power shaft and said tap-spindle drive-shaft; a tap-reverse drive between said power shaft and said tap-spindle drive-shaft; and automatic means for alternately rendering effective said forward and reverse drives.

32. A machine-tool combining a translatable tool-head; a plurality of tap-spindles rotatably carried thereby; taps carried by said spindles; a tap-spindle drive-shaft; an operative connection between said drive-shaft and said tap-spindles; a power shaft; a tap forward-drive mechanism between said power shaft and said tap-spindle drive-shaft; and means actuated by said forward-drive mechanism for lowering said tool-head at a speed proportionate to the speed of rotation of said tap-spindles.

33. A machine-tool combining a translatable tool-head; a spindle rotatably carried thereby; a spindle drive-shaft; an operative connection between said spindle drive-shaft and said spindle; a forward-drive mechanism for said spindle drive-shaft; a reverse-drive mechanism for said spindle drive-shaft; and means actuated by said reverse-drive mechanism to elevate said tool-head.

34. A machine-tool combining a translatable tool-head; a spindle rotatably carried thereby; a spindle drive-shaft; an operative connection between said spindle drive-shaft and said spindle; a forward-drive mechanism for said spindle drive-shaft; a reverse-drive mechanism for said spindle drive-shaft; a feed-screw having a threaded engagement with said tool-head; means actuated by said spindle forward-drive for rotating said feed-screw in one direction to lower said head; and means actuated by said reverse-drive for rotating said feed-screw in the opposite direction to elevate said head.

35. A machine-tool combining a translatable tool-head; a spindle rotatably carried thereby; a spindle drive-shaft; an operative connection between said spindle drive-shaft and said spindle; a forward-drive mechanism for said spindle drive-shaft; a reverse-drive mechanism for said spindle drive-shaft; a feed-screw having a threaded engagement with said tool-head; means actuated by said spindle forward-drive for ro-

tating said feed-screw in one direction to lower said head; means actuated by said reverse-drive for rotating said feed-screw in the opposite direction to elevate said head; clutches embodied in each of said forward and reverse drives; and automatic means for alternately engaging said clutches.

36. A machine-tool combining a translatable tool-head; a spindle rotatably carried thereby; a spindle drive-shaft; an operative connection between said spindle drive-shaft and said spindle; a forward-drive mechanism for said spindle drive-shaft; a reverse-drive mechanism for said spindle drive-shaft; a feed-screw having a threaded engagement with said tool-head; means actuated by said spindle forward-drive for rotating said feed-screw in one direction to lower said head; means actuated by said reverse-drive for rotating said feed-screw in the opposite direction to elevate said head; clutches embodied in each of said forward and reverse drives; a clutch-shifter for each of said clutches; rotatable cams operatively connected with said clutch-shifters; and means for rotating said cams to cause said clutch-shifters alternately to engage said clutches.

37. A machine-tool combining a translatable tool-head; a feed-screw having a threaded engagement with said tool-head; a spindle rotatably carried by said tool-head; a spindle drive-shaft operatively connected with said spindle; a power shaft; a spindle forward-drive mechanism including speed-reduction gearing between said power shaft and said spindle drive-shaft; and a feed-screw rotating mechanism operatively connected with said speed-reduction gearing, said last-named mechanism also including speed-reduction gearing whereby said feed-screw is rotated at a slower rate than said spindle drive-shaft.

38. A machine-tool combining a translatable tool-head; a feed-screw having a threaded connection with said tool-head; power actuated means for rotating said feed-screw; manual means for rotating said feed-screw; and automatic means for alternately rendering effective said power and manual means.

39. A machine-tool combining a translatable tool-head; a feed-screw having a threaded connection with said tool-head; power actuated means for rotating said feed-screw; manual means for rotating said feed-screw; and means, actuated by the upward movement of said tool-head, to disconnect said power feed and to render effective said manual feed.

40. A machine-tool combining a translatable tool-head; a feed-screw having a threaded connection with said tool-head; power-actuated means for rotating said feed-screw; manual means for rotating said feed-

screw; said power actuated and manual means each including a clutch; a feed-shaft co-axial with said clutches; and means for alternately actuating said clutches to cause them alternately to engage said feed-shaft.

41. A machine-tool combining a translatable tool-head; a feed-screw having a threaded connection with said tool-head; a feed-shaft operatively connected with said feed-screw; a clutch carried by said feed-shaft; a power shaft, a driving connection between said power shaft and said clutch for rotating the latter from the former; a second clutch on said feed-shaft; manual means for rotating said second clutch; and automatically actuated means for operating said clutches to cause one to be connected to said feed-shaft and to simultaneously therewith disconnect the other from said feed-shaft.

42. A machine-tool combining a translatable tool-head; a feed-screw having a threaded connection with said tool-head; a feed-shaft operatively connected with said feed-screw; a clutch carried by said feed-shaft; a power shaft; a driving connection between said power shaft and said clutch for rotating the latter from the former; a second clutch on said feed-shaft; manual means for rotating said second clutch; a single clutch-shifter for actuating both of said clutches; a rotary cam operatively connected with said clutch-shifter; and means to rotate said cam to cause it to actuate said clutch-shifter alternately in opposite directions to alternately connect said clutches to said feed-shaft.

43. A machine-tool combining a translatable tool-head; a feed-screw having a threaded connection with said tool-head; a feed-shaft; an operative connection between the feed-shaft and the feed-screw to rotate the latter from the former; power means for rotating said feed-shaft; a normally inoperative clutch coaxial with said feed-shaft; manual means for rotating said clutch; and means for disconnecting said power means and simultaneously therewith connecting said clutch to said feed-shaft to permit manual rotation of the feed-shaft.

44. A machine-tool combining a translatable tool-head; a plurality of sets of spindles carried thereby, a plurality of trains of mechanism adapted to translate said head and to rotate said spindles; a cam-shaft; cams carried by said cam-shaft; operative connections between said cams and said trains of mechanism to control the action of the latter; means to rotate said cam-shaft; and means for intermittently actuating said cam-shaft rotating means.

45. In a machine-tool in combination, a rotatable shaft; means for intermittently rotating said shaft, said means including a power shaft; a gear on said rotatable shaft;

a driving connection between said power shaft and the gear on said rotatable shaft, said driving connection including a cycle-control clutch; and means for periodically disconnecting said clutch to break said driving connection.

46. A machine-tool combining a translatable head; a plurality of spindles rotatably carried thereby; a power shaft; means actuated by said power shaft for translating said head; means actuated by said power shaft for rotating said spindles; a rotatable shaft; cams carried by said rotatable shaft; means actuated by said cams for controlling the operation of said head-translating means and said spindle rotating means; a driving connection between said power shaft and said rotatable shaft; and means for interrupting said driving connection.

47. In a machine-tool, in combination, a translatable tool-head; spindles rotatably carried thereby; means for moving said tool-head in opposite directions; means for rotating said spindles in opposite directions, said means including a power shaft; a spindle drive-shaft; a feed screw having a threaded connection with said tool-head; an operative connection between said power shaft and said feed-screw; an operative connection between said power shaft and said spindle drive-shaft; and automatically actuated means for controlling the action of said operative connections and thereby the direction of feed of the head and rotation of the spindles.

48. The combination as set forth in claim 47 characterized by this, that the automatically actuated means for controlling the direction of feed and rotation of the spindles includes a plurality of clutches; and cam-actuated means for actuating said clutches in a predetermined order to effect a complete cycle of operation of the machine-tool.

49. The combination set forth in claim 47 characterized by this, that the automatically actuated means for controlling the direction of feed of the head and rotation of the spindles includes a plurality of clutches; a cam-shaft; a plurality of cams carried by said cam-shaft; clutch-shifters operatively engaging said clutches and actuated by said cam; and means for rotating said cam-shaft to intermittently actuate said clutches.

50. In a machine-tool, a plurality of trains of mechanism adapted to be operated intermittently; a rotatable shaft; means carried by said rotatable shaft to control the action of said trains of mechanism; and a cycle control mechanism for controlling the rotation of said rotatable shaft, said cycle control mechanism comprising a continuously rotating gear; a normally stationary member; a gear connection between said member and said shaft; automatic actuated means

for periodically clutching said gear to said member to give to the latter and to said shaft partial rotations; and means to disconnect said gear from said member.

5 51. In a machine-tool, a plurality of trains of mechanism adapted to be operated intermittently; a power shaft; a cam shaft; an operative connection between said power shaft and said cam shaft; cams carried by 10 said cam shaft to control the action of said trains of mechanism; and a cycle-control mechanism embodied in the operative connection between the power shaft and the cam shaft for controlling the rotation of said 15 cam shaft.

52. A machine-tool combining a translatable tool-head; a power shaft; a plurality of trains of mechanism actuated by said power shaft to translate said tool-head; a 20 rotatable member; means carried by said rotatable member for controlling the action of said trains of mechanism; a cycle control mechanism adapted to control the rotation of said rotatable member; said cycle control 25 mechanism including a power transmitting clutch; and means actuated by the movement of said head for rendering said clutch ineffective to transmit power.

53. In a machine-tool, a power shaft; a 30 driven shaft; power-transmitting mechanism operatively connecting said shafts, said mechanism including a cycle-control device comprising a jack-shaft, a continuously rotatable gear journaled on the jack-shaft; a member fixed to said jack-shaft; a clutch 35 adapted to connect said member and said gear; a gear connection between said jack-shaft and said driven shaft; a disk rotatably journaled coaxial with said jack-shaft; a driving connection between said member and 40 said disk to rotate the latter from the former; means for stopping the rotation of the disk; and means, rendered active by the stopping of the disk, to disconnect clutch.

45 54. A cycle-control mechanism comprising a shaft; a first gear freely rotatable coaxial with said shaft; a second gear fixed to said shaft; a member fixed to said shaft; a clutch mechanism between said member and 50 said first gear; a disk rotatably journaled coaxial with said member; an impositive driving connection between said member and said disk; means to arrest the rotation of said disk and means actuated by the stoppage 55 of the disk to disengage said first gear from said member.

55. A cycle-control mechanism comprising a shaft; a first gear freely rotatable coaxial with said shaft; means to rotate said gear; 60 a member fixed to said shaft; means operatively connecting said member with said gear; a disk rotatably journaled coaxial with said member; a plurality of recesses formed in said disk; a plurality of detents carried by said member and adapted

to contact with said gear and to engage said recesses to rotate said disk with said member; means active during a continued rotation of said gear to arrest the rotation of said disk; cam-surfaces provided by said recesses 70 and adapted upon stoppage of the disk to move said detents laterally to cause relative lateral movement between said gear and said member to disconnect the one from the other.

56. A machine-tool combining a translatable head; means for translating said head; a power shaft; a driven shaft; driving means operatively connecting said shafts; said driving means including a cycle-control mechanism adapted to control the rotation of said driven-shaft; a clutch embodied in said cycle-control mechanism; means for shifting said clutch to break said driving connection, said last-named means including a normally rotatable disk; dogs adapted to be placed in the path of said disk to arrest the rotation of the latter; means actuated by said disk to disconnect said clutch when said disk is stopped; and means actuated by the movement of said head to withdraw 80 said dogs from the path of said disk to permit further rotation of the latter.

57. A machine-tool combining a translatable head; means for translating said head; an abutment carried by said head; a power shaft; a driven shaft; a driving connection between said shafts; a clutch embodied in said driving connection; means normally tending to disengage said clutch to break said driving connection, said means including a rotatable disk and a dog normally intersecting the path of movement of said disk; and means actuated by said abutment to remove said dog from the path of said disk to permit said clutch to become effective. 105

58. A machine-tool combining a translatable tool-head; means for translating said head; a power shaft; a cam-shaft; a plurality of cams carried by said cam-shaft, a plurality of mechanisms actuated by said 110 cams; means for rotating said cam-shaft from said power shaft, said last-named means including a cycle-clutch; a plurality of dogs for rendering said cycle-clutch ineffective; a plurality of abutments carried 115 by said tool-head; and means actuated by said abutments for successively removing said dogs from their effective positions to permit intermittent partial rotations of said cycle-clutch.

59. A clutch-operating device comprising a shaft; a member slidably secured to said shaft; a cam provided by said member; a clutch-shifter having one end engaging the clutch to be shifted and its other end engaging said cam; an abutment for said member; a pressure device acting on said member to normally hold the latter against said abutment, said pressure device being constructed and arranged to yield under the 125 130

action of said cam after the clutch has been engaged.

60. A clutch-operating device comprising a shaft; a member rotatable with said shaft; a clutch-shifter having one portion in engagement with the clutch to be operated; actuating means provided by said member and engaging said clutch-shifter to actuate the latter, said means being constructed and 10 arranged to give said shifter a greater throw than is necessary to actuate the clutch; and means to receive the balance of the throw of the actuating means after the clutch has been engaged.
15. 61. A clutch-operating device comprising a shaft; a member slidably secured to said shaft; a cam provided by said member and having a throw greater than the movement required to actuate the clutch; a fixed abutment; a coil-spring engaging said slidably member and acting normally to hold the latter against the abutment; a clutch-shifter having one portion in engagement with the clutch to be operated and another portion 20 engaging said cam; and means to rotate said shaft to cause said cam to operate said clutch-shifter, said spring acting to receive the excess throw of said cam.

62. A clutch-operating device comprising a shaft; a member slidably secured to said shaft; a cam provided by said member; a clutch-shifter having one end in engagement with the clutch to be operated and another end engaging said cam; means to rotate said shaft to cause said cam to actuate said clutch-shifter; and means rendered active by further rotation of said shaft to place said clutch-shifter under tension to forcibly maintain the clutch in engagement under a 30 predetermined pressure.

63. A combined drilling and tapping machine comprising a translatable tool head; a plurality of sets of spindles carried thereby; drills secured in the spindles of one set;

taps secured in the spindles of another set; 45 means to rotate said drill spindles uni-directionally; means to rotate said tap spindles in forward and reverse directions; means to translate said tool-head in opposite directions; means to change the direction of rotation of the tap spindles simultaneously with the change in direction of movement of the tool-head; and means simultaneously to present work to the drills and taps.

64. A combined drilling and tapping machine comprising a tool-head; two independent sets of spindles rotatably carried thereby; means to rotate one of said sets of spindles uni-directionally; means to rotate the other set of spindles multi-directionally; 50 drills secured in the uni-directionally driven set of spindles; taps secured in the spindles of the other set; means to present work beneath said drills and taps; and means actuated by the tap spindle drive and in synchronism therewith to effect relative vertical movement between said drills and taps and said work.

65. A combined drilling and tapping machine comprising a translatable head; two 55 sets of spindles carried thereby; means for rotating the two sets of spindles at materially different rates; means for reversing the direction of rotation of one set of spindles; drills secured in the spindles of one 70 set; taps secured in the spindles of the reversible set; a work-support adapted to sustain a plurality of pieces of work; means to move said work-support in a plane transverse to the axis of said spindles to place the work 75 carried thereby in position to be acted on by said drills and taps; and means for effecting relative movement between said work-support and said drills and taps in a direction lengthwise of said spindles.

In witness whereof, I hereunto subscribe my name.

CHARLES A. STICKNEY.
